UNITED STATES PATENT OFFICE

2,141,993

CONSTRUCTION TOY

Florence Van Dyck Kreider, Lebanon, Pa.

Application October 11, 1938, Serial No. 234,458

3 Claims. (Cl. 46—11)

This invention relates to a construction toy, and it is primarily an object of the invention to provide a shoe box or the like having suitable indications thereon whereby the box can be readily converted into a toy cradle without the use of paste or other fastenings.

5 The invention also has for an object to provide a shoe box or the like with suitable indications to denote the lines of cut to be made by 10 scissors or other cutting implement to permit the box to be converted into a cradle.

The invention consists in the details of construction and in the combination and arrangement of the several parts of my improved construction toy whereby certain important advantages are attained and the device rendered simplified, less expensive and otherwise more convenient and advantageous for use, as will be hereinafter more fully set forth.

20 The novel features of my invention will hereinafter be definitely claimed.

In order that my invention may be the better understood, I will now proceed to describe the same with reference to the accompanying drawings, wherein:—

Figure 1 is a view in perspective of a construction toy in accordance with an embodiment of my invention;

Figure 2 is a view in perspective with the toy 30 assembled;

Figure 3 is a longitudinal sectional view taken through the device as illustrated in Figure 2.

As disclosed in the accompanying drawing, B denotes the body portion of a box, such as used 35 in connection with shoes or the like, the bottom and side walls of the body B being made of cardboard or kindred relatively heavy stock. The side walls i of the body B each has produced on the outer face thereof by imprinting, scoring or 40 as otherwise desired an arcuate line 2 disposed on such a radius as to extend from substantially one end of the outer free straight edge a of the wall i to the opposite end thereof. This line 2 denotes a line of cut which may be readily made 45 by scissors or other cutting implement and the portion R cut out from the side wall i is of such form and configuration to constitute a rocker.

The bottom wall 4 of the body B at a point 50 closely adjacent to each end wall 5 is provided thereacross on its outer face with a line b which may be made by imprinting, scoring or as otherwise desired and each end of the line b is continued by the line c on the outer face of each side wall i. This line c extends upwardly from the

bottom wall 4 to a desired distance thereabove and is also positioned close to an adjacent end wall 5. A slit is to be cut across the bottom wall 4 along each of the lines b and upwardly of each side wall i along the line c. The resultant kerf 5 6 snugly receives the straight end portion of a rocker R. The rocker R also frictionally engages within a slit 6 thus facilitating the maintenance of the converted toy in assembled relation.

While I do not wish to limit myself to a body 10 B of any particular dimensions yet in practice it is preferred that the body B be of such size as generally used in connection with shoes for children.

From the foregoing description it is thought 15 to be obvious that a construction toy constructed in accordance with my invention is particularly well adapted for use by reason of the convenience and facility with which it may be assembled and operated, and it will also be obvious 20 that my invention is susceptible of some change and modification without departing from the principles and spirit thereof and for this reason I do not wish to be understood as limiting myself to the precise arrangement and formation of the 25 several parts herein shown in carrying out my invention in practice except as hereinafter claimed.

Altho the foregoing description mentions only 30 specifically a shoe box, and preferably a shoe box for infants' or children's shoes, it is of course to be understood that the invention is not limited thereto but is equally applicable for embodiment in boxes of other various kinds or for other various purposes.

35 I claim:—

1. A construction toy comprising a box body having a bottom wall and side walls of a material to be cut by scissors or other cutting implement, the bottom wall of the box body closely 40 adjacent to the ends thereof being provided therealong with lines to indicate lines of cut, said lines having their end portions continued upwardly of the side walls of the box body, the side walls of the box body and the upper portions 45 thereof being also provided with arcuate lines to denote lines of cut.

2. A construction toy comprising a box body having a bottom wall and side walls of a material to be cut by scissors or other cutting implement, 50 the bottom wall of the box body closely adjacent to the ends thereof being provided therealong with lines to indicate lines of cut, said lines having their end portions continued upwardly of the side walls of the box body, the side walls of the 55

box body and the upper portions thereof being also provided with arcuate lines to denote lines of cut, the arcuate line on each side wall extending from substantially one end of the upper 5 or free marginal edge of the side wall to substantially the opposite end thereof.

3. A construction toy comprising a box body having a bottom wall and side walls of a material to be cut by scissors or other cutting implement, the bottom wall of the box body closely 10

adjacent to the ends thereof being provided therealong with lines to indicate lines of cut, said lines having their end portions continued upwardly of the side walls of the box body, the side walls of the box body and the upper portions thereof being also provided with arcuate lines to denote lines of cut, said lines of the bottom wall and the side walls being on the outer surfaces thereof.

FLORENCE VAN DYCK KREIDER. 10
